Primary Examiner — Paul D Bohannon

(57)

CLAIM

The ornamental design for a seat shell as shown and described.

DESCRIPTION

1. Seat shell

1.1 : Perspective

1.2 : Front

1.3 : Back

1.4 : Left

1.5 : Right

1.6 : Top

1.7 : Bottom

Description of the reproductions: **1.1** is a front perspective view, **1.2** is a front view, **1.3** is a rear view, **1.4** is a left side view, **1.5** is a right side view, **1.6** is a top view and **1.7** is a bottom view.

1 Claim, 7 Drawing Sheets
